UNITED STATES PATENT OFFICE.

JUAN B. RAMIREZ, OF WARREN POINT, NEW JERSEY.

PIN.

1,100,446.

Specification of Letters Patent. Patented June 16, 1914.

Application filed August 19, 1912. Serial No. 715,866.

To all whom it may concern:

Be it known that I, JUAN B. RAMIREZ, a citizen of the United States, residing at Warren Point, in the county of Bergen and State of New Jersey, have invented certain new and useful Improvements in Pins; and I do declare the following to be a full, clear, and exact description of the invention, such as will enable others skilled in the art to 10 which it appertains to make and use the same.

This invention relates to pin fasteners, and more especially to those adapted for connecting sheets of paper, although the pin 15 is not at all so limited in its use and, in fact, in some essential particulars it might be designed for the purpose of connecting other articles than sheets of paper.

The objects of the invention are, first, to 20 reduce the likelihood of sticking the fingers or engaging the pin point with other objects while it is in place; second, to shape the pin in such manner that the sheets of paper will lie as flat as possible while connected; and third, to provide means whereby 25 the pin will be held against accidental displacement, although yet permitting it to be manually withdrawn at any time. These and other objects are accomplished by making the shank of the pin straight throughout 30 most of its length and deflecting its extremities in opposite directions to a slight degree and on curved lines rather than angularly. In the following specification and 35 claims will be found the details of construction of several embodiments of this idea, as shown in the accompanying drawings wherein:—

Figure 1 is a side elevation of the simplest form of this pin, having an ordinary head, the same conforming nearly to the construction of the ordinary toilet pin now in every day use. Fig. 2 is a front elevation and a side elevation of a pin whose shank 40 is formed in the same manner but whose head is flattened and herein shown as formed into an eye. Fig. 3 is a front elevation and a side elevation of a similar pin whose flattened head is formed into the shape of a 45 loop bent back over the shank of the pin. Figs. 4, 5 and 6 are diagrammatic views showing the manner of inserting the pin through a flat piece of paper. Figs. 7 and 8 are similar diagrammatic views showing 50 how the pins of Figs. 2 and 3 could be inserted through a piece of paper.

In all views of the drawings, the numeral 1 designates the shank of the pin which is preferably perfectly straight, being made of round, fine wire, as usual, and of the desired gage and length and finish; and in Fig. 1 I have shown at 2 how this shank may be roughened as by the formation of notches therein, if desired. The lower end of the shank is continued into what we will call a "rearward" bend 3, beyond which is the tip 4 having a pointed extremity 5, and the length of the tip is unimportant as is also the exact degree of its deflection out of the axial line of the shank 1. By the dotted lines in Fig. 1 it will be seen that such deflection is something less than 45°. This detail is not material, although it is to be noted that the bend 3 is a gentle curve and there is a distinct absence of any pronounced angle at this point. The outer or upper end of the shank is bent in an opposite or what we might call a "forward" direction at the point 6, beyond which it is continued in a neck 7 whose length is preferably about that of the tip 4 and whose angularity is probably about the same so that these two portions of the pin stand in parallel lines, as the dotted lines will show in Fig. 2. The bend 6 again avoids angles, and is struck on a gentle curve as shown, and for purposes which will appear hereinafter.

The head of this pin may be variously formed. In Fig. 1 it is a small button or flattened disk 8 standing in a plane out of the axis of the shank and at right angles to the length of the neck 7 which is rigidly attached to its center; in Fig. 2 the head 9 is formed in the shape of an eye or a small ring, but in this case it stands slightly oblique to the line of the neck 7 and in a plane parallel with the axis of the shank 1; and in Fig. 3 the head 10 is formed in the shape of a loop or ring of considerable size, but instead of upstanding from the neck 7, it hangs pendant from the same although it is rigidly connected therewith at the point 11, and here again the plane of the head 10 is parallel with that of the shank 1. These illustrations will be sufficient to emphasize the fact that the gist of the present invention lies in the shape of the shank and the neck and tip thereof, and the shape and disposition of the head of the pin will depend upon its use. It is quite possible that a large or fancy head could be formed on or attached to the same, or the pin could become

a part of some other device without departing from the principle of the invention. As to the head, I would say that I prefer that it shall be flat and shall stand out of a plane which would extend through the axis of the shank 1 or neck 7.

Figs. 4, 5 and 6 illustrate the manner in which a pin of this character is inserted through a sheet of paper, and for sake of 10 simplicity and clearness I have illustrated but a single sheet although in use the pin will doubtless connect two or more superimposed sheets. Fig. 4 shows the first step after the pointed extremity 5 has been passed 15 through the paper sheet P and the tip 4 pushed through the hole 12' in the direction of the arrow 12, so that the bend 3 will lie within the hole in the paper. To insert the pin in this manner, the operator who would 20 be at the point 13, would first turn the pin so that its tip 4 would be toward him and its head 8 away from him, pass the point 5 downward through the paper and move the tip in the direction of the arrow 12, and 25 then turn the entire pin downward in the direction of the arrow 14. Fig. 5 shows the next step where the straight shank 1 has been slipped through the hole in the paper and the tip 4 is about to be passed upward 30 in the direction of the arrow 15, and the operator accomplishes this step with my improved pin in precisely the same manner that he would use an ordinary pin, but with the advantage that the upturned tip 4 is in 35 position to penetrate the paper P for the second time with extreme ease, and no bend whatever has yet been made in the sheet of paper. Fig. 6 illustrates the third step, or rather the position of parts after the pin has 40 been put into place. When the tip has passed through the paper the second time, as it is about to do in Fig. 5, continued movement in the direction of the arrow 16 causes the entire pin to rotate on its axis automatically for a one-half revolution, by reason of the fact that the deflected neck 7 as it passes through the first perforation 12' in the paper brings out this automatic rotation as a result of pressure in the direction 16. 45 The rotation occurs while the pin is passing through the second perforation 17 in the paper and continues until it comes to rest as shown in Fig. 6; the result is that the paper is forcibly bent upward slightly at 50 the point 18 so that the lower end of the shank 1 may pass through the second perforation 17 in an oblique direction, as shown. But the advantage resulting is that the rearward bend 3 finally comes to rest just below 55 said second perforation 17, and the point 5 of the pin is turned downward toward the paper and caused to rest thereon. The result is that the operator will not be likely to 60 prick his fingers on the point, nor catch or 65 tear other pieces of paper thereon. It should

be noted also that the paper is bent upward but once and to an extremely slight degree, and the flattened head (whatever its form) lies close upon or against the flat portion of the paper next to the perforation 12', and avoids the well known "hump" which is found in all commercial papers that are connected by the ordinary pin now in daily use, and whose head stands at that time on edge or in a plane at right angles to the axis of its shaft rather than in a plane oblique thereto as shown in Fig. 6 or parallel therewith as shown in Figs. 7 and 8. Any form of flattened head used in connection with my improved pin facilitates the rotation above referred to or at least permits it, and if the head be amplified as shown in Figs. 2, 3, 7 and 8, the fact that it is larger and flattened gives it a larger bearing surface on the paper to prevent the pin shank from turning over so that the point would stand upward.

In removing the pin from its position illustrated in Figs. 6, 7 and 8, it is only necessary to grasp the head and draw upward or toward the numeral 19 which would be away from the operator, meanwhile giving the head a partial rotation after the neck 7 has passed out of the perforations 12'. At this time the tip 4 has passed out or is passing out of the perforation 17, so that the partial rotation restores the parts to the position shown in Fig. 5; and thereafter it is an easy matter to lift the pin upward and withdraw it from the first perforation 12' in the paper P in a manner which will be clear.

As suggested above, I do not limit the use of this pin to paper. In fact, it is quite obvious that, while it could be passed through one or more sheets of paper as shown in the drawings without creating an undesirable "hump" therein, it could be used to equal advantage on fabrics whether the same were flexible or highly starched, and in its insertion and withdrawal it would not make an unsightly hole or cause the material to be crimped or bent to a great degree.

It will be unnecessary for the purposes of this specification to go into the manner of making the pin, or give any details as to its size, material, and unimportant details.

I am aware that hitherto efforts have been made to deflect the shaft or shank of a pin out of a true straight line for the purpose of causing it to remain in place securely, or causing it to worm or screw itself into place as it is inserted. But, my improved pin differs from others of which I am aware to the extent that its "shank" so-called is perfectly straight throughout its entire length and is deflected on gentle curves and without any angles into relatively short and unimportant members herein called the "tip" and the "neck" which stand oblique to the axis of the shank and on opposite sides thereof.

I consider the use of a downturned tip 4

of advantage in holding the point 5 against the paper P, only when the neck 7 is upturned in the opposite direction so that when in place this neck will hold the tip with its point 5 against the paper rather than permitting it to turn over and project upward; and, of course, the use of a flattened head but more firmly prevents the rotation of the pin after it has been put in place.

10 My improved head avoids undue bending of the material P by having the deflected neck 7 adjacent the head of the pin, and in no case will I dispose said head in a plane at right angles to the axis of the shank, or in

15 the plane thereof.

What is claimed as new is:—

1. The herein described pin comprising a relatively long straight shank, bent aside at one end and continued into a relatively short straight tip standing oblique to the axis of the shank and having a pointed extremity, the other end of the shank being bent aside in the opposite direction into a relatively short neck, and a flattened head at the outer end of said neck standing wholly out of the line of the shank and in a plane transverse to the common plane of said shank, tip, and neck.

2. A pin having a straight shank bent aside and continued into a short tip standing oblique to the axis of said shank and having a pointed extremity, the other end of the shank being bent into a short neck extending in a direction opposite to said tip, and a flattened head at the outer end of said neck 35 standing out of line with the axis of the shank but in a plane parallel therewith.

3. A pin having a straight shank bent aside on a curve and continued into a short straight tip standing oblique to the axis of 40 said shank and having a pointed extremity, the other end of the shank being bent on a curve into a short neck extending in a direction opposite to said tip, and a flattened 45 loop-shaped head at the outer end of said neck standing out of line with the axis of the shank but in a plane parallel therewith and transverse to the plane of said bends.

In testimony whereof I have hereunto set my hand in presence of two subscribing witnesses.

JUAN B. RAMIREZ.
